UNITED STATES PATENT OFFICE.

MARK B. CLAFF, OF RANDOLPH, MASSACHUSETTS.

STAYED BOX COVERING AND METHOD OF PRODUCING THE SAME.

Application filed January 22, 1923. Serial No. 614,085.

To all whom it may concern:

Be it known that I, MARK B. CLAFF, a citizen of the United States, residing at Randolph, county of Norfolk, Commonwealth of Massachusetts, have invented certain new and useful Improvements in Stayed Box Coverings and Methods of Producing the Same, of which the following is a specification.

10 This invention relates to the art of covering boxes with paper, and particularly to a stayed or reinforced paper box covering and the method of and apparatus for producing such a covering and the resultant 15 box or cover.

Various forms of stayed paper box coverings have been devised and several methods for producing said blanks are in use, but so far as I am aware such previous blanks, 20 boxes and methods have all been open to certain objections which my present invention seeks to overcome.

One characteristic objection to existing paper box coverings has arisen from the difficulty in applying the stay strips to the covering blank. Heretofore the covering blanks and stay strips have usually been separately cut and then glued to each other. This method involves several distinct cutting operations or handling, including that of notching the stay strips at the points where the covering blank folds about the corners of the box, and not only slows down production but introduces a factor of uncertainty in respect to the application of the stay strips to the blank. Moreover, the stay strips are located across the transverse lines of fold of the covering blank and are exposed to view when the blank is folded 40 about the box.

According to my invention the paper covering blank is stayed along its longitudinal edges by a pair of relatively tough stay strips, preferably of heavy kraft paper, 45 which are adhesively affixed to the blank during the formation of the blank itself. These strips are placed just outside of that area of the blank which covers the body portion of the box and terminate short of the longitudinal margins of the box and are turned over the corners of the box when the longitudinal flaps of the blank are overfolded. Inasmuch as said strips do not ex-

tend quite to the margins of the covering blank, they will therefore be completely concealed by the blank when folded about the box.

As contemplated herein, the paper from which the covering blanks are formed is fed as a continuous strip which is slit or notched at a plurality of points in its length to define the lines of cut-off for the blanks and to constitute the end notches which lie at the corners of the box when the individual blanks are severed from the strip and folded around the box.

Moreover, the stays are fed as continuous strips simultaneously with the feed of the strip from which the individual covering blanks are cut. The strips preferably are attached to the covering blank outside the line of slitting or notching so that they are uninterrupted and unweakened during feeding. They are severed by the same knife which cuts the strips into individual blanks. This insures that the strips will be of the same length as the covering blanks and avoids the necessity of independently severing or handling of the stay strips.

I am able therefore not only to obtain increased speed of production by simultaneously feeding and severing the covering blank and stay strips, but I also secure positive accuracy of placement of the stay strips relative to the individual covering blanks when slit or severed. Moreover, the simultaneous feed of both the blank strip and the stay strips enables said strips to be adhesively coated as they are drawn from the supply rolls, thus insuring that they will be adequately coated with adhesive. Furthermore, at the moment of cut-off from the strip the blanks are in position to receive the box and may therefore be applied while the glue is fresh. This avoids the necessity for extra handling of the covering blanks and does not give the blanks a chance to dry and become curled.

As illustrative of my invention, I have shown in the accompanying drawings a novel stayed paper box covering blank and method of producing the same, and also a new box structure produced by my method and characterized by certain features which add materially to its strength and perfection of form. Throughout the specification and

drawings like reference characters are correspondingly applied, and in the drawings:—

Fig. 1 is a somewhat diagrammatic illustration of equipment for the practice of my invention.

Fig. 2 is a plan view of the same.

Fig. 3 is a view showing the cover strip and stay strip united and ready to be severed adjacent the box.

Fig. 4 is an inverted view showing a severed blank in its feed relation to a partly covered box, and

Fig. 5 a plan view of the stayed and severed strip.

Referring first to Figs. 4 and 5, the box to be covered is indicated at B and the body portion 1 of the paper covering blank C is shaped to correspond to the size and shape 20 of the top and bottom panels of the box, and has end flaps 2 and side flaps 3 which are adapted to be turned over the end and side walls of the box as indicated at the right in Fig. 4.

The stay strips S are applied longitudinally of the longitudinal edges of the covering blank at a point just beyond the limits of the body portion 1 of the blank and terminate short of the edge of said blank on 30 each side. Said strips are as long as the blank itself and are folded across the end walls of the box when the side flaps 3 of the blank are tucked in, and thus are completely concealed by the end flaps 2 of the blank 35 when said flaps are folded upwardly against the end walls of the box. This results in a strong and permanent reinforcement at all four corners of the box.

The blank C is slotted or notched at its 40 corners to form a mitre as indicated at 4, the cut just missing the underlying stay strips S, whereby the stayed blank may be fitted about the corners of the box without weakening the stay strips. The slit 4 adjacent the corner of the blank is in reality half of an angular slit made by the blade 8 in the cover strip as it is drawn along. Heretofore such blanks have usually been 45 died out with a triangular shaped opening for a similar purpose. In accordance with my invention, however, by making this cut a slit rather than an opening I am able to get greater strength as stock left by the knife cut may be brought around the corners of the box as shown in the partly formed box in Fig. 4. I prefer this knife 50 cut for this reason, but obviously the blanks may be mitred in the usual manner if desired.

The method of and apparatus for producing my novel stayed covering blank will now be described. Referring to Fig. 1, I have indicated at 6 a supply roll 6 for the web of paper from which the covering blanks C are to be successively cut. On the same

spindle with the supply roll 6 are a pair of supply rolls 7 for the webs of paper, muslin, or other suitable reinforcing material from which the stay strips S are drawn. The stay strips S are so guided by the clips G 70 relative to the blank strip for the covering blank strip C as to position the stay strips longitudinal of the blank strip and slightly inset from the edges thereof.

The strips C and S are simultaneously 75 drawn from their supply rolls by suitable feed rolls F. The strip C is up to or slightly including the strip S simultaneously slit or died out at definite points by an angle blade 8 and plate 9 between which the strips feed. The angular slits produced by said knives define the longitudinal extent of the individual covering blanks.

From the knife 8 the strips C and S are 80 drawn over a glue drum 10 operating in a glue pan 11 whereby all strips are adhesively coated. After passing the glue drum the cover strip is carried upwardly over a tension roll 12 while the stay strips are 85 guided to its margins as described. The united strips now pass the feed rolls F to a cut-off knife 13 which severs the strips C and S centrally across the angle of the slits formed therein. The individual blanks with 90 their reinforcing strips accurately measured and united thereto are then ready for and adjacent to the forming block 14 for application to a box blank B which has been put on the block 14 by the operative. The block 14 supports the box blank B in longitudinal alignment with the strip; that is to say, with the longer dimensions of the box or cover longitudinally of the strip, and the shorter dimensions or ends transversely of the strip. This gives maximum reinforcement 95 along the major length of the box and the greatest possible reinforcement across the shorter end of the box over which the strips are folded.

Various modifications in the construction and operation of my device may obviously be resorted to, all without departing from the spirit of my invention if within the limits of the appended claims.

What I therefore claim and desire to secure by Letters Patent is:—

1. The method of forming a box covering consisting in continuously forming a blank by drawing off a covering sheet, in continuously attaching to the margins thereof a longitudinal reinforcing strip, and in successively making paired angled cuts each twice the length of the mitre cut of the unitary blank, and each pair spaced from the cut pair next preceding so that the angle centers are a full blank length apart and in severing each blank across the line of the angle centers.

2. The method of forming a covered box 130 consisting in continuously forming a com-

bined blank by simultaneously drawing off and embodying a covering sheet and longitudinal stay strips, and in applying the same to a formed box blank and in end 5 folding and tucking in the same.

3. A web assembly for covering and staying a box shell, consisting of a continuous web of covering material slitted adjacent its margins and severed across said slits to 10 provide covering blanks each having side flaps and corner flaps attached to the ends of the side flaps, and two continuous webs of stay material adhesively united to said covering web marginally thereof and disposed as attached stay strips coextensive in length with the side and corner flaps of the covering blank when the blank is severed from the covering web.

4. A web assembly for covering and staying a box shell, consisting of a continuous web of covering material mitre-cut adjacent its margins and severed across said mitre-cuts to provide covering blanks each having side flaps and corner flaps attached to 25 the ends of the side flaps, and two continuous webs of stay material adhesively united to said covering web outside of the mitre-cuts of the web and disposed as attached stay strips co-extensive in length 30 with the side and corner flaps of the covering blank when the blank is severed from the covering web.

5. The method of forming a stayed covering blank having side flaps and corner flaps attached to the ends of the side flaps which consists in simultaneously drawing off a covering sheet and a pair of longitudinal stay strips, in adhesively attaching said strips along the longitudinal edges 40 of said covering sheet, and in simultaneously severing said sheet and strips to provide covering blanks with attached stay strips coextensive in length with the side and corner flaps of the severed blanks.

45 6. The method of mitre-cutting and staying a covering blank having side flaps and corner flaps attached to the ends of the side flaps, which consists in simultaneously drawing off a covering sheet and a pair of marginal stay strips, in successively making in 50 said sheet adjacent the margins thereof opposed pairs of mitre-cuts, each pair being spaced apart a distance of one blank length from the pair immediately preceding it, in 55 adhesively attaching said strips along the longitudinal edges of said covering sheet, and in simultaneously severing said sheet and strips across the line of said mitre cuts to provide covering blanks with attached 60 stay strips coextensive in length with the side and corner flaps of the severed blank.

7. The method of mitre-cutting and stay-

ing a covering blank having side flaps and corner flaps attached to the ends of said side flaps, which consists in simultaneously drawing off and adhesively attaching to each other a continuous covering sheet and a pair of marginal stay strips, in successively making in said sheet adjacent the margins thereof pairs of oppositely disposed angle cuts, 65 each angle cut being twice the length of the mitre-cut of the unitary blank when said blank is severed from the sheet, and each opposite pair of cuts being spaced apart a distance of one blank length from the pair of cuts immediately preceding it, and in successively severing the sheet across the line of the angle centers of each pair of cuts to provide individual blanks in which the mitre-cuts at the ends of the blank are 70 constituted by the halves of the oppositely disposed pairs of angle cuts, and in which the attached stay strips are coextensive in length with the side and corner flaps of the severed blank.

8. The method of mitre-cutting and severing covering blanks for box shells from a continuously fed covering sheet, which consists in successively making in said sheet adjacent the margins thereof pairs of oppositely disposed angle cuts, the apices of each opposite pair of cuts being spaced apart a distance of one blank length from the apices of the pair of cuts immediately preceding it, and in successively severing the sheet across the apices of each pair of cuts to provide individual blanks in which the mitre-cuts at the ends of the blank are 85 constituted by the halves of the oppositely disposed pairs of angle cuts.

9. The method of mitre-cutting and severing the covering blanks for box shells from a continuously fed covering sheet, which consists in successively making in said sheet adjacent the margins thereof pairs of oppositely disposed angle cuts, each angle cut being twice the length of the mitre cut of the unitary blank when said blank is severed from the sheet, and the apices of each opposite pair of cuts being spaced apart a distance of one blank length from the apices of the pair of cuts immediately preceding it, and in successively severing the sheet across the apices of each pair of cuts to provide individual blanks in which the mitre cuts at the ends of the blank are constituted by the halves of the oppositely disposed pairs of angle cuts.

In testimony whereof I affix my signature in presence of two witnesses.

MARK B. CLAFF.
